UNITED STATES PATENT OFFICE.

LOUIS T. FREDERICK, OF WILKINSBURG, PENNSYLVANIA, ASSIGNOR TO WESTINGHOUSE ELECTRIC & MANUFACTURING COMPANY, A CORPORATION OF PENNSYLVANIA.

ADJUSTABLE-PITCH PROPELLER.

Application filed May 15, 1919. Serial No. 297,353.

To all whom it may concern:

Be it known that I, LOUIS T. FREDERICK, a citizen of the United States, and a resident of Wilkinsburg, in the county of Allegheny and State of Pennsylvania, have invented a new and useful Improvement in Adjustable-Pitch Propellers, of which the following is a specification.

My invention relates to propellers and more particularly to propellers of the adjustable-pitch type, and it has, for its primary object, the provision of a propeller of such character embodying composite molded blades.

Heretofore, adjustable-pitch propellers have been made in which a propeller hub was provided with diametrically disposed, tubular, blade-receiving arms in which the inner ends of wooden propeller blades were secured for turning movement, and means was mounted upon the hub, or within the same, for turning or tilting the blades to vary their pitch and to hold the blades in adjusted position.

One object of my invention consists in providing sleeves which may be mounted for turning movement within the arms of a hub and which may be actuated by the usual blade-tilting mechanism and which are adapted to hold the inner ends of molded blades of composite material.

A still further object of my invention resides in the provision of means for molding the blades in the sleeves so as to securely anchor them thereto.

With these and other objects in view, my invention will be more fully described, illustrated in the drawings, in the several views of which corresponding numerals indicate like parts, and then particularly pointed out in the claims.

Fig. 1 is a rear elevation of part of my improved propeller; Fig. 2 is a plan view, partly in section; Fig. 3 is a rear elevation of the hub portion, partly in section, and Fig. 4 is an end view of the hub, partly in section.

My propeller comprises a hub 1 formed with diametrically disposed tubular arms 2 to receive sleeves 3 in which are secured the inner ends of the propeller blades 4.

The outer end of each arm 2 is internally beveled to form a seat and externally threaded, as best shown in Fig. 2. Each sleeve 3 is

formed, at its inner end, to fit snugly within 55 the inner portion of its receiving arm 2 for free turning movement and, near its outer end, with an annular shoulder 5, one face of which is beveled to engage the seat of the arm and the opposite face of which receives a bearing race 6 having bearing balls 7. A locking ring 8 is threaded about the end of each arm and has a flange 9 which engages the race 6, whereby the race is held in place and the sleeve 3 is secured within 65 the arm for free turning movement.

The blades 4 of my improved propeller may preferably be formed of fibrous material and a suitable binder, such as a phenolic condensation product, which has been 70 hardened by the application of heat and pressure.

For example, a blade may comprise superimposed layers of fibrous sheet material, such as paper or duck impregnated with a 75 binder, such as a phenolic condensation product. The impregnated sheets may be assembled in the manner disclosed in a copending application filed by me Dec. 30, 1918, Serial No. 268,954, (Case No. 6283) or 80 in the manner disclosed in a copending application filed by D. A. Dickey, Dec. 30, 1918, Serial No. 268,949, (Case No. 6187) and assigned to the Westinghouse Electric & Manufacturing Company. The assembled 85 blade may then be disposed in a mold of any suitable character and cured by subjecting it to heat and pressure to compact and shape it and to harden the binder.

Preferably the inner ends of the blades 90 are formed with a tapered socket 10 for the sake of lightness and are molded directly into the sleeves 3. If such is the case, wedge rings 11 are forced into the inner ends of the blades during the molding operation 95 to expand such ends and force them into engagement with the flaring inner ends of the sleeves so as to securely lock the blades to the sleeves. If desired, the inner faces of the sleeves and the outer faces of the 100 wedge rings may be roughened to more securely engage the molded material of the blades.

Slidably mounted upon the rear end of the hub 1 is a shifting collar 12 which is 105 keyed or otherwise secured to the hub to turn therewith. The shifting collar includes an inner portion which turns with

the hub and an outer portion 13 which is connected to the inner portion by a bearing race 14 so that it may remain stationary while the hub and inner portion revolve.

- 5 Any suitable control lever or link (not shown) may be connected to the outer portion 13 so that, while the propeller is in operation, the shifting collar may be reciprocated upon the hub. Pivotally connected, 10 to the inner member of the collar are blade tilting levers 15 which pass through slots 16 formed in the arms of the hub and through aligned openings in the inner ends of the sleeves and propeller, 15 blades, as best shown in Figs. 2 and 4.

As the blade-shifting mechanism forms no part of my invention, a more detailed description is deemed to be unnecessary. It should, however, be noted that reciprocation 20 of the shifting collar 12 upon the hub will cause reverse tilting of the blades so that their pitch may be varied, at will, during flight.

From the foregoing description, it will 25 be apparent that I have provided an effective and economical means of constructing a propeller of the variable-pitch type in which the blades may be of a molded composition, such as a fibrous material and 30 a hardened binder. It will also be clear that, by molding the blades directly into the hub-engaging sleeves, absolute securing of the blades to the hub is insured.

Obviously, various changes in construction 35 may be resorted to and, for this reason, no limitations are to be imposed upon my invention other than those set forth in the claims.

I claim as my invention:

1. An adjustable-pitch propeller comprising a hub having radial tubular arms, tapered sleeves rotatably mounted on the arms, means for adjustably turning the sleeves, and composite propeller blades having their inner ends molded into the sleeves. 40

2. An adjustable-pitch propeller comprising a hub, tapered sleeves having adjustable connection with the hub, and propeller blades, the inner ends of which are molded 45 into the sleeves.

3. An adjustable-pitch propeller comprising blades of fibrous material and a heat-hardened binder, tapered sleeves into which the inner ends of the blades are molded, and a hub adapted to receive the sleeves. 50

4. In an adjustable-pitch propeller, a sleeve internally flared at one end, a propeller blade of fibrous material and a hardened binder having its inner end disposed within the sleeve and molded therein, and means 60 molded into such end of the blade for expanding it in the flared portion of the sleeve.

5. In an adjustable-pitch propeller, a sleeve internally flared at one end, a propeller blade of fibrous material and a hardened binder having its inner end disposed within the sleeve, such end of the blade being formed with a recess, and a wedging member forced into the recess to expand 70 the adjacent portion of the blade into the flared portion of the sleeve. 65

In testimony whereof, I have hereunto subscribed my name this 30th day of April 1919.

LOUIS T. FREDERICK.
